UNITED STATES PATENT OFFICE.

ALONZO PERINGTON READ, OF CHICAGO, ILLINOIS.

DESIGN FOR A WASHER.

SPECIFICATION forming part of Design No. 29,023, dated July 12, 1898.

Application filed February 13, 1897. Serial No. 623,329. Term of patent 7 years.

To all whom it may concern:

Be it known that I, ALONZO PERINGTON READ, a citizen of the United States, residing at Chicago, in the county of Cook and State 5 of Illinois, have invented a new and original Design for Washers on Door and Window Stops or Beads, of which the following is a specification, reference being had to the accompanying drawings.

My design is illustrated in the accompanying drawings, in which—

Figure 1 is a face or plan view of the washer. Fig. 2 is a sectional view thereof.

The leading features of my design consist 15 of a flat base A, a flat face B, parallel with the base A but of less length; the face B merging into a convex-curved edge C, which terminates at the base A, and a central circular opening D, extending through the washer, of 20 less diameter than the length of the flat face B and having inclined walls converging to-

ward the base A, which gives to the washer a characteristic and distinguishing appearance.

My design gives the washer the appearance of a substantially flat disk with a quadrant-shaped edge connecting the opposite faces of the washer and having a central opening with sloping or inclined walls converging from the face to the base of the washer, thus giving to the washer a new, a characteristic, and a distinguishing appearance.

Having thus fully described my invention, what I claim as new, and desire to secure by Letters Patent, is—

The design for a washer substantially as 35 herein shown and described.

In testimony whereof I affix my signature in presence of two witnesses.

ALONZO PERINGTON READ.
